Specification for Design.

Patented Mar. 7, 1916.

Application filed November 29, 1915. Serial No. 64,168. Term of patent 14 years.

To all whom it may concern:

Be it known that I, EDWIN C. McGRAW, a citizen of the United States, residing at East Palestine, in the county of Columbiana and State of Ohio, have invented a certain new, original, and ornamental Design for Rubber Tires, of which the following is a specification, reference being had to the accompanying drawing, forming part thereof.

Figure 1 is a plan view of a segment of a tire showing my design; Fig. 2 is a transverse section.

I claim:—

The ornamental design for a rubber tire as shown.

In testimony whereof I have hereunto signed my name.

EDWIN C. McGRAW.
